RAILWAY SIGNALING SYSTEM

Clark A. Pickell, Rochester, N. Y., assignor to
 General Railway Signal Company, Rochester,
 N. Y.

Application September 11, 1940, Serial No. 356,346

11 Claims. (Cl. 246—33)

This invention relates to a railway signaling system of the absolute-permissive-block type having or not having superimposed thereon a centralized traffic controlling system for governing the movement of track switches and for clearing the starting signals at the entrance to the single track sections in which, if superimposed control is added, said starting signals are normally held at stop, and relates more particularly to means for indicating in a central office the condition of occupancy of the entire single track section of such system in a simple and economical manner.

A single track section connecting two passing sidings in an A. P. B. system having two intermediate double signal locations ordinarily employs six track relays in such single track section. By reason of the distance that many of these track relays are located from a coding unit in a code type system it would be prohibitive, by reason of the line wires which would have to be added, to transmit to the central office the positions assumed by such track relays.

In accordance with the present invention it is proposed to provide circuits and relays at the two ends of a single track section, which circuits and relays in combination transmit through the medium of the code type system having a field coding unit at each end of said single track section, accurately the fact whether the single track section is occupied or unoccupied. More specifically, it is proposed to use the home relay at one entrance end to a single track section in combination with an approach relay indicating the condition of energization of the next opposing home relay for controlling the control circuits which manifest occupancy of the single track section.

Other objects, purposes and characteristic features of the present invention will in part be described hereinafter and the several specific embodiments thereof are shown in Figs 1A, 1B and 1C, Fig. 2 and Fig. 3 of the drawings. Figs. 1A, 1B and 1C if laid side by side in that order conveniently show one system embodying the present invention and Figs. 2 and 3 show how the system of Fig. 1 may be modified to constitute a second and a third embodiment.

Referring to the drawings with Figs. 1A, 1B and 1C laid side by side in this order, these drawings show two passing sidings PS1 and PS2 which are connected by a single track section including track circuited blocks X, Y and Z. Each of these blocks is provided with a centrally fed track circuit including a battery BX, BY or BZ and a track relay at each end of such block. These

track relays have been designated by the reference character T having a prefix corresponding to the signal which such track relay directly controls. The passing siding PS1 is connected to the single track section comprising block X, Y and Z by a switch SW1, whereas the passing siding PS2 is connected to this single track section by a track switch SW2. Traffic is governed into the west end of the single track section by the starting signals S2 and S2A for trains leaving the main track and side track of the passing siding PS1, respectively. Similarly, traffic may be governed into the east end of the passing siding by starting signals S1 and S1A. The signals for governing east bound traffic through and out of the single track section have been designated S4, S6 and S8, whereas the signals governing west bound traffic through and out of the single track section have been designated S5, S3 and S1. Although the present invention may be applied to any suitable type of A. P. B. system only a few specific forms of such a system have been illustrated and in order to get a better understanding of the first specific system illustrated in Fig. 1 the circuits and apparatus located at each intermediate signal will be briefly described. Since the apparatus at each of these intermediate signals is the same as that at any other intermediate signal location the description of the apparatus associated with intermediate signal S4 will suffice.

Although this signal S4 may be of any suitable construction, such as a semaphore signal, a search-light signal of the movable spectacle type on a multi-unit light signal, for convenience a multi-unit light signal only has been illustrated.

This signal S4 is preferably provided with three light units, one light unit of which if lighted will emit a green beam as designated by the letter G and signifying clear traffic conditions, another unit of which if lighted will emit a yellow beam as designated by the letter Y and signifying caution traffic conditions, and another of which units will emit a red beam and signifying danger traffic conditions, as designated by the letter R. These lamps G, Y and R are preferably controlled by a neutral contact 10⁴ and a polar contact 11⁴ of a home and distant relay 4HD. This home-distant relay 4HD although it may be a slow releasing relay of any type is preferably a relay of the polar retained-neutral type. This polar retained-neutral relay may be of a construction such as illustrated in the patent to Field, No. 2,180,583, dated November 21, 1939.

As shown, relay 4HD is energized by a circuit

including a front contact 12^4 of the relay $4T$, a front contact 13^5 of the track relay $5T$, a back contact 14^5 of the directional stick relay $SR5$ and a front contact 15^6 of the home-distant relay $6HD$ located at the next signal $S6$ in advance. This same circuit has another branch through the medium of which the relay $4HD$ may be energized by current of negative polarity, and this branch circuit includes the back contact 15^6 of the home-distant relay $6HD$ and also includes a front contact 16^6 of the directional stick relay $SR6$.

These directional stick relays SR are controlled in a well known and usual manner and by referring to signal $S4$ it will be seen that the relay $SR4$ may be picked up through a circuit including the back contact 18^4 of the track relay $4T$ and the front contact 19^4 of the home-distant relay $4HD$ in series. Upon picking up of this directional stick relay $SR4$ it will be stuck up through a stick circuit including its own stick contact 20^4 and the back contact 18^4 of the track relay $4T$. Dropping of the track relay $4T$ to pick up the stick relay $SR4$ will also result in the dropping of relay $4HD$ by opening of its front contact 12^4 . Since, however, the neutral armature of the home-distant relay $4HD$ is of the retained type the front contact 19^4 of this relay $4HD$ will not open until the stick relay $SR4$ has picked up. Upon eventual dropping of the relay $4HD$ a second stick circuit is closed for the stick relay $SR4$. This second stick circuit includes the stick contact 20^4 and the back contact 21^4 of the relay $4HD$ in series.

It is thus seen that the directional stick relay $SR4$ can only be picked up when east-bound traffic passes the signal $S4$, and that it will remain stuck up until this train has entirely left the block Y as will be evidenced by the picking up of the relay $4HD$. This picking up of the relay $4HD$ will break the second stick circuit for the relay $SR4$, the first stick circuit having been broken when the track relay $4T$ picked up, allowing dropping of this stick relay $SR4$. The intermediate signals $S3$, $S5$ and $S6$ are controlled in a similar manner as just described for the signal $S4$ and for this reason like elements associated with the signals $S3$, $S5$ and $S6$ have been designated by like reference characters as those for signal $S4$, but having distinctive exponents, prefixes or subfixes.

Since the starting signals associated with the entrance end of a single track section and since the exit signals for such single track sections, for a particular direction of traffic, are dependent upon the positions of the track switches at the entrance end and at the exit end respectively, and since no direction relays are associated therewith, these signals are specifically controlled differently and the control circuits for these signals will now be briefly described.

Referring to Fig. 1A the track switch $SW1$ may be controlled by a switch machine SM , which is controlled by circuits including a front contact 25^1 of a lock relay $L1$ and interlocked contacts controlled by the normal relay $1NW$ and the reverse relay $1RW$ in any well known and usual manner, as conventionally illustrated by the dotted line 26^1 . These switch control relays $1NW$ and $1RW$ are preferably controlled through the medium of a code type system which has been conventionally shown by the office code sending and receiving unit O , the field code sending and receiving unit $F1$ shown in Fig. 1A, and the field code sending and receiving unit $F2$ 75

shown in Fig. 1C. This code type communicating system may be of any suitable construction, such for instance, as disclosed in the patent to Preston and Bushnell, No. 2,155,561, dated April 25, 1939. The position of the track switch $SW1$ is preferably indicated by a suitable switch indication relay $WP1$, which is preferably of the polar-neutral type and is preferably picked up to a particular polar position only when the track switch assumes a particular extreme position and providing the switch is locked in that position.

It will be seen that the starting signals $S2$ and $S2A$ are normally held at stop. This is accomplished by the signal control relay RGZ shown in the field code sending and receiving unit $F1$, which relay RGZ shown as a neutral relay, but may be of any other suitable construction, is normally in its deenergized dropped away position. This signal control relay RGZ may also be a relay of the mag-stick polar type. This relay RGZ through the medium of its front contacts $18R$ and $19R$ may energize either the signal relay $2G$ or the signal relay $2AG$ depending on the polar position assumed by the switch repeating relay WP at that time. These relays $2G$ and $2AG$ being further or additionally controlled by the back contact 30^1 of the lock relay $L1$, front contact 31^1 of the detector track relay $DT1$, front contact 32^2 of the relay $2HD$ and front contact 33^1 of the relay $WP1$. The relay $2G$ when energized and picked up will result in placing the signal $S2$ in either its caution or its clear condition depending on the polar position assumed by the contact 36^2 of the relay $2HD$, this picking up of the relay $2G$ also extinguishing the red lamp R of the signal 2 by opening of the back contact 37^2 of the relay $2G$. If the switch repeater relay $WP1$ assumes its left-hand energized position signifying that the track switch $SW1$ assumes the take-siding position the picking up of the relay RGZ will energize the relay $2AG$ which will result in the clearing of the dwarf starting signal $S2A$ by lifting of its contact 40^2 . This picking up of relay $2AG$ presumes the detector track relay $DT1$ and the relay $2HD$ to be energized and the lock relay $L1$ to be deenergized. This picking up of the signal relay $2AG$ will, however, also by the opening of its back contact 41^2 open the energizing circuit for the signal-at-stop relay $M1$, which in turn by opening of its front contact 42^1 will open the energizing circuit for the home-distant relay $3HD$. This circuit for relay $3HD$ in addition to the usual track relay contacts 12^3 , 13^2 and 17^1 also includes the contact 23^1 of the relay $1G$. In a similar manner as the relay $M1$ is deenergized by opening of the contact 41^2 of relay $2AG$ this relay $M1$ may be deenergized by the opening of back contact 43^2 of the relay $2G$. If desired the relay $M1$ may be omitted, in which case the contacts 41^2 and 43^2 will be included in series in the circuit of the relay $AE1$.

The relays $1G$ and $1AG$ are controlled in a manner similar to that in which the relays $2G$ and $2AG$ are controlled, and since the switch $SW1$ is locked so long as any signal governing traffic thereover is at proceed, suitable means must be provided to manually hold signals $S1$ and $S1A$ at stop. For convenience the manual control for these signals has been omitted. The relay $1G$ to be energized requires the lock relay $L1$ to be down and the relays $DT1$ and $1HD$ to be up and further is dependent on the position assumed by the polar contact 44^1 of the switch indication relay $WP1$. The relay $1G$ has included in its energizing circuit the front contacts 46^1

and 47¹ of relays DT¹ and 1HD and the back contact 45¹ of the lock relay L1. Relay 1AG is controlled similarly to relay 1G but does not include the contact 47¹ of relay 1HD. Signal S1 is controlled by contacts 50¹ and 51¹ of relays 1G and 1HD in the same manner as signal S2 is controlled by contacts 37² and 36² of relays 2G and 2HD. Also, the lamps of signal S1A are controlled by contact 52¹ of relay 1AG in the same manner as the lamps of signal S2A are controlled by contact 40² of relay 2AG.

Let us now observe how the relays XR¹ and XR² are controlled so as not to be deenergized due to dropping of the home-distant relay of the associated starting signal when that relay is dropped due to a tumble-down of signal relays started from the opposite end of the single track section but is deenergized if a train passes the associated starting signal and deenergizes its associated home-distant relay. This same construction also prevents the dropping of the relay XR¹ or XR² due to the manual clearing of a starting signal at either the same end or the opposite end even though such clearing of a starting signal will cause a tumble down of home-distant relays to take place. The relay XR¹ is normally energized through a circuit including the front contact 55² and the polar contact 56² in its right-hand position of the home-distant relay 2HD and upon deenergization of the home-distant relay 2HD may be energized through the back contact 55² of this relay and the front contact 57¹ of the approach relay AE¹. Since the entrance of a train into the west end of the single track stretch deenergizes both of these relays 2HD and AE¹ (unless relay AE¹ has been previously deenergized due to dropping of the relay M¹) the relay XR¹ will be dropped due to such entrance of an east bound train in that end irrespective of whether or not one of the starting signals S2 or S2A had been previously cleared.

Dropping of the relay XR¹ will through the medium of the code type communicating system above referred to cause the code responsive relay IXR¹ to operate its contacts 61 to the right, where they will remain by permanent magnet stick action. The dropping of the relay XR¹ will initiate the code communicating system by momentary opening of the starting circuit at its contact 58¹, and the closing of back contact 59¹ will generate the proper code element to operate the relay IXR¹ in the office to the right, which by closing contact 61 will energize indicating relay X. The picking up of relay X by closure of its front contact 63 will close an energizing circuit for the indicating lamp IX to manifest by its illumination that the single track section is occupied. If desired the relay X may be omitted, in which case the contacts 61 and 62 in multiple (Fig. 1A) or in series (Fig. 3) will be included in the energizing circuit of the indicating lamp IX.

In a similar manner and through the medium of this communicating system the indicating relays IR¹ and IR² are operated to the right to illuminate their respective indicating lamps I¹ and I² through contacts 65 and 66 of these relays when the detector track relays DT¹ and DT², respectively, are dropped, as by track occupancy. For instance, the dropping of the detector track relay DT¹ may initiate the communicating system by momentarily opening the starting circuit through the medium of its contact 68¹ after which the closed condition of contact 69¹ will transmit the proper code element to operate the indicating

relay IR¹ to the right to illuminate the lamp I¹. Since the apparatus and signals associated with track switch SW² are identical to those associated with the track switch SW¹ they have been assigned like reference characters having distinctive exponents, prefixes and suffixes.

Operation of Fig. 1.—Let us assume that there is an east-bound train occupying the main track of the passing siding PS¹ which is about to pass through the single track stretch, and let us observe how the presence of this train in the single track stretch is indicated by the illumination of the indicating lamp IX so long as any part of this train occupies the single track section. In order to allow such train movement the starting signal S2 must first be manually cleared. The operator in the central office O will operate a suitable lever LG¹ which in turn will through the medium of the code communicating system heretofore referred to, cause energization of the east-bound signal control relay RGZ (R signifying right-hand direction). The energization of the relay RGZ closes its front contact 18R resulting in the energization of the signal relay 2G. Picking up of this relay 2G causes deenergization of the signal-at-stop relay M¹, which in turn by the opening of its contact 42¹ causes deenergization of the home-distant relay 3HD and also causes deenergization of the approach relay AE¹. Dropping of the home-distant relay 3HD places the signal S3 in its stop position and by the opening of its front contact 15³ causes deenergization of the home-distant relay 5HD. Dropping of the relay 5HD places the signal S5 in the stop condition and by the opening of its contact 15⁵ causes deenergization of the home-distant relay 7HD, which in turn prevents either of the starting signals S1 or S1A being cleared. Dropping of the approach relay AE¹ did not accomplish any particular function except to open its front contact 57¹ which becomes important only upon deenergization of the home-distant relay 2HD.

The picking up of the signal relay 2G by the opening of its back contact 37² opens the energizing circuit for the red lamp of the signal S2 and by the closing of its front contact 37² causes energization of the green lamp G of this signal S2. This is based on the assumption that the home-distant relay 2HD is energized to its right-hand positive position as would be the case when the single track section is unoccupied. The east-bound train in question may now, in response to the clearing of the signal S2, move into the single track section and when its first axle enters the detector track section containing the detector track relay DT¹ this track relay will be deenergized and by the opening of its contact 31¹ will deenergize relay 2G and place the signal S2 in its stop position, but this will not cause the illumination of the indicating lamp IX in the central office O because the single track section is not yet occupied and will not be occupied until the train has passed over the switch SW¹. In this connection it may be pointed out that the switch SW¹ may also be controlled from the central office O through the medium of a lever LW¹ and the code communicating system and through the medium of switch control relays 1NW and 1RW which control the switch machine SM through the medium of circuits conventionally shown by the dotted line 26¹.

As the train proceeds into the single track section it will cause deenergization of the track relay 2T, which in turn by the opening of its contact 12² will cause deenergization of the home-

distant relay 2HD. The dropping of the relay 2HD by the opening of its front contact 55² will break the energizing circuit for the relay XR1, the auxiliary circuit for this relay also being opened at the front contact 57¹ of the approach relay AE1. Dropping of the relay XR1 and its contacts 58¹ and 59¹ causes a code to be transmitted to the central office resulting in the operation of the indicating relay IXR1 to the right. This will in turn cause energization of the indicating relay X and the illumination of the indicating lamp IX.

As the east-bound train proceeds through the single track section and passes the signal S4 it will cause deenergization of the home-distant relay 4HD and will cause energization of the directional stick relay SR4 for reasons heretofore pointed out. This will cause reenergization of the home-distant relay 2HD, but at this time the relay 2HD will be energized by current of negative polarity and to the left so that even though the front contact 55² of this relay is closed the energizing circuit for the relay XR1 remains open because the polar contact 56² is in its left-hand position. As this east-bound train passes the signal S6 it causes deenergization of the home-distant relays 6HD and causes energization of the directional stick relay SR6. Since the energizing circuit for the home-distant relay 6HD has included in series therein the approach relay AE8 this approach relay AE3 is also deenergized and dropped away. Since the home-distant relay 7HD was heretofore deenergized by reason of the tumble-down effect the indicating relay XR2 at the east end of the single track section is now deenergized and this causes the code type communicating system to be initiated by the momentary opening of the contact 58² of this relay XR2. Also, the closing of the back contact 59² of this relay XR2 transmits the proper code element through the medium of the communicating system to operate the contact 62 of the relay IXR2 in the control office to the right-hand position. This results in a second energizing circuit for the indicating relay X being completed. As the train proceeds in an eastwardly direction and entirely passes out of the block Y the home-distant relay 4HD is again energized (with negative polarity in this instance) and by the closure of its front contact 15⁴ completes the normal energizing circuit for the relay 2HD which results in the return of the polar contact 36² and 56² to its right-hand position resulting in the reenergization of the relay XR1. The picking up of the relay XR1 transmits a code to the central office resulting in the operation of the indicating relay XR1 to its left-hand position. Since, however, the indicating relay X is now energized by a circuit including the closed contact 62 of the relay IXR2, the indicating lamp IX remains lighted; manifesting that the single track section is still occupied.

As the train in question proceeds in an east-bound direction and passes the signal S8 it causes deenergization of the detector track relay DT8, which in turn, for reasons heretofore described, causes illumination of the indicating lamp I2 in the central office. As the last wheels and axles of the east-bound train pass out of the block Z, and assuming that the operator has in the meantime returned his lever LG1 to the stop position to deenergize the relay RGZ, the home-distant relay 7HD is reenergized (as are also home-distant relays 1HD, 3HD and 5HD) by current of positive polarity. This results in energization of

relay XR2 and the transmission of a code to the central office resulting in the return of the indicating relay IXR2 to its left-hand position, which in turn causes the indicating lamp IX to be extinguished manifesting that the single track section is no longer occupied.

If the operator has, however, not returned his lever to the stop position the home-distant relay 7HD is not reenergized. In this case, however, 10 the home-distant relay 6HD and the approach relay AE8 included in series therewith are reenergized as soon as the train has cleared the detector track circuit to reclose the contact 17⁸ of the detector track relay DT8. With the relay 15 AE8 energized and the home-distant relay 7HD still deenergized the relay XR2 is reenergized through a circuit including back contact 52⁷ of the relay 7HD and the front contact 57⁸ of the relay AE8. This will result in the deenergization 20 of the indicating relay X in the control office and in extinguishment of the indicating lamp IX. In a similar manner as just described the indicating lamp IX is also illuminated during the west-bound passage of a train through the single track section.

There may be instances where it is not desirable to provide supervisory manual control over the starting signals but at the same time desire an indication of the condition of occupancy of the 30 single track section. In this event, the signal control relays GZ and their contacts 18 and 19 would be omitted as would also be the contact 42 of the relay M. In this case the auxiliary circuit for the relays XR, and including a back contact 35 55 of the home-distant relay of the starting signal and a front contact 57 of the approach relay AE, would be entirely omitted. Such an arrangement has been illustrated in Fig. 2 of the drawings. In this modified form of the invention the 40 tumble-down function is started when the train passes the starting signal and since this deenergizes the home-distant relay for the starting signal at the far end, this will by the opening of the front contact 55 of such home-distant relay result in the deenergization of the relay XR at the far end and in the illumination of the indicating lamp IX. The home-distant relay for the starting signal at the exit end of the single track section will, of course, remain in the deenergized condition until the train has entirely departed from the single track section at which time this home-distant relay is reenergized and the indicating lamp is extinguished.

In many instances there is only one pair of intermediate signals. Such an arrangement has been illustrated in Fig. 3 of the drawings. By referring to Figs. 1A, 1B and 1C it is readily seen that if only one pair of intermediate signals is employed, the home-distant relay for the starting signal will not return to its normal positively energized condition until a train which entered that end has passed entirely out of the single track section. Also, the home-distant relay for the starting signal at the exit end is deenergized through tumble-down action when a train enters the entrance end and remains deenergized until the train has entirely departed from the single track section. In other words, if the relays XR1 and XR2 were controlled as indicated for the relay XR1 in Fig. 2, then the contacts 61 and 62 instead of being connected in multiple, as shown in Fig. 1A, could be connected in series, and if so connected the indicating relay X would be energized so long as there is a train in the single track section, irrespective of the direction of movement of the train through

the single track section. A system so constructed has been illustrated in Fig. 3 of the drawings. In this construction, although the tumble-down function takes place when the train passes the starting signal and before it passes over the track switch, the indication of occupancy by the illumination of lamp IX does not take place until the train has actually entered the single track section just beyond this track switch. This is true even though the home-distant relay for the starting signal at the exit end drops before the train has actually entered the single track section because the indication is not given by illumination of lamp IX until the home-distant relays for the starting signals at both ends of the single track section are in their non-clear (positively energized) condition. Also, this indicating lamp IX is extinguished the moment the last axle leaves the single track section and when the train still occupies the detector track section at the exit end.

The applicant has thus illustrated conventionally and described rather specifically three embodiments of the present invention. It should, however, be understood that these illustrations are merely exemplary of the nature of the invention and that various changes, additions and modifications may be made to adapt the invention to the particular problem encountered in practicing the invention without departing from the spirit and nature of the invention, except as demanded by the scope of the following claims.

What is claimed as new is:

1. In combination, a single track section divided into blocks and connecting two passing sidings, a starting signal at each end of said single track section for governing the movement of traffic into said section from that end, an entering signal at each end of said single track section for governing the movement of traffic out of said single track section and into the connected passing siding, intermediate signals for governing traffic in each direction through said single track section, there being one such intermediate signal at the entrance to each block, a home relay for each starting signal and each intermediate signal, a track circuit for each block each including a normally energized track circuit, a circuit for each home relay including a front contact of the track relay of the block in advance and a front contact of the home relay for the signal next in advance, manually controlled means for each end of said single track section to normally hold said starting signal for that end at stop and which if operated allows clearing of such signal dependent upon the energized condition of its associated home relay and simultaneously therewith deenergizes the home relay for the first opposing signal, whereby the clearing of a starting signal at one end of said single track section successively deenergizes the home relays for all opposing signals, a central office, an indicating lamp in said central office indicating by its condition of illumination the condition of occupancy of said single track section, and means governed by the condition of energization of said home relays for said starting signals for causing the illumination of said indicating lamp when a train occupies said single track section, said means acting to prevent the illumination of said indicating lamp when one of said home relays is deenergized due to the manual clearing of a starting signal.

2. In combination, a single track section divided into blocks and connecting two passing sidings, a starting signal at each end of said single track section for governing the movement of traf-

fic into said section from that end, an entering signal at each end of said single track section for governing the movement of traffic out of said single track section and into the connected passing siding, intermediate signals for governing traffic in one direction and intermediate signals for governing traffic in the other direction through said single track section, there being one such intermediate signal at the entrance to each block, a home relay for each starting signal and each intermediate signal, a track circuit for each block each including a normally energized track circuit, a circuit for each home relay including a front contact of the track relay of the block in advance and a front contact of the home relay for the signal next in advance, whereby the entrance of a train into one end of said single track section successively deenergizes the home relays for all opposing signals, a central office, an indicating lamp in said central office indicating by its condition of illumination the condition of occupancy of said single track section, an approach relay at each end of said single track section included in series with the home relay for the first opposing signal, and means governed by the first opposing signal, and means governed by the home relay and the approach relay at a particular end of said single track section for governing said indicating lamp to illuminate such lamp when said single track section is occupied.

3. In combination, a section of single track connecting two passing sidings, signals at each end of said section governing train movements into and out of said section, intermediate signals in said section for governing the movement of traffic in both directions in said section, a signal relay for each signal except the last for each direction of traffic energized normally through a front contact of the signal relay of the signal next in advance, a directional stick relay for each signal except the first for closing an energizing circuit for the signal relay for the signal next in the rear if the block in advance is occupied by a train moving in a direction to be governed by such signals, an approach relay at each end of said section included in series with the signal relay of the first opposing signal, a central office, an indicating lamp in said central office indicating by its condition of illumination the condition of occupancy of said section, and means governed by the signal relay of the first signal and by its associated approach relay for each direction of traffic for governing said indicating lamp to give an occupancy indication only when said single track section is occupied.

4. In combination, a section of single track connecting two passing sidings, signals at each end of said section governing train movements into and out of said section, intermediate signals in said section for governing the movement of traffic in both directions in said section, a signal relay for each signal except the last for each direction of traffic energized normally through a front contact of the signal relay of the signal next in advance, a directional stick relay for each signal except the first for closing an energizing circuit for the signal relay for the signal next in the rear if the block in advance is occupied by a train moving in a direction to be governed by such signals, an approach relay at each end of said section included in series with the signal relay of the first opposing signal, a central office, an indicating lamp in said central office indicating by its condition of illumination the condition of occupancy of said section, and a relay for controlling the energization of said indicating lamp

energized by two circuits one of which includes a front contact of the signal relay of said first signal and the other of which includes a front contact of said approach relay.

5. In combination, a section of single track connecting two passing sidings, signals at each end of said section governing train movements into and out of said section, intermediate signals in said section for governing the movement of traffic in both directions in said section, a polar relay for each signal except the last for each direction of traffic energized normally through a front contact of the polar relay of the signal next in advance, a front contact of a track relay of the next block in advance and by current of positive polarity, a directional stick relay for each signal except the first for closing an energizing circuit for the polar relay for the signal next in the rear energized by current of negative polarity if the block in advance is occupied by a train moving in a direction to be governed by such signals, an approach relay at each end of said section included in series with the polar relay of the first opposing signal, a central office, an indicating lamp in said central office indicating by its condition of illumination the condition of occupancy of said section, and a relay for controlling the energization of said indicating lamp energized by two circuits one of which includes a front contact of the polar relay of said first signal and the other of which includes a front contact of said approach relay in series with a back contact of said polar relay for said first signal.

6. In a single track railway system signaled by absolute-permissive-block signaling, the combination with a single track stretch connecting two passing sidings, signals including a starting signal for each end for governing the movement of traffic into that end and one or more intermediate signals for governing traffic in each direction through the stretch, a signal relay having polar and neutral contacts for each signal, a normally closed energizing circuit for each signal relay except the last including a front contact of the signal relay for the next signal in advance, a directional stick relay for each intermediate signal, a second energizing circuit for each signal relay except the last including a front contact of the directional stick relay for the signal next in advance, means for causing successive deenergization of said signal relays for one direction of traffic when a train moving in the opposite direction enters said stretch, and for energizing each directional stick relay as such train passes each intermediate signal, a track occupancy indicator for indicating occupancy of said stretch, an approach relay for each end of said section included in series with the signal relay for the first opposing signal, and means for controlling said indicator including one circuit through a front neutral contact and a polar contact of the signal relay for a starting signal and another circuit including a back contact of such signal relay and a front contact of its associated approach relay.

7. In a single track railway system having a stretch of single track between two passing sidings with starting signals for governing the movement of traffic into said stretch in each direction together with intermediate signals in the stretch, an absolute-permissive-block signaling system with superimposed manual control having relays associated with said starting signals for governing the indication of such signals to permit one or the other to display clear in response to manual control and at the same time cause the

opposite starting relay to remain at stop, said system also permitting either starting signal to display caution or clear for a following train with one or two blocks spacing respectively, a single track indicator for indicating when illuminated the occupied condition of said stretch of track, and means controlled by contacts of the relays associated with both said starting signals for illuminating said indicator whenever either starting signal displays caution or stop due to the presence of a train in said stretch, said means being ineffective when a starting signal indicates stop due to said manual control.

8. In a single track railway system having a stretch of single track connecting two passing sidings, a starting signal at each end of said stretch for governing the movement of traffic into said stretch from that end, one or more intermediate signals for governing traffic in each direction through the stretch, said signals acting to divide said stretch into a plurality of track sections, track relays for each of said track sections, a signal relay for each of said signals, an energizing circuit for each of said signal relays controlled by front contacts of the track relays for the track section next in advance of its associated signal and in accordance with traffic conditions in advance of that section, manually controlled means associated with each starting signal for holding that signal at stop but acting when operated to allow such starting signal to clear and at the same time to deenergize the circuits for the signal relays for each of the signals governing the opposite direction of traffic, a single track indicator lamp in a central office for indicating when illuminated the occupied condition of said stretch, a communication system extending between the central office and said starting signals, indication circuit means associated with each starting signal for transmitting a track occupied indication to said central office only when its signal relay is deenergized due to the presence of a train, said indication circuit means being ineffective to transmit such indication when its signal relay is deenergized in response to a manual control for allowing an opposing starting signal to clear, and circuit means in the central office responsive to the reception of a track occupied indication over said communication system from either of said starting signals for energizing said single track indicator.

9. In a railway system having a stretch of single track connecting two passing sidings, a starting signal and one or more intermediate signals for governing traffic in each direction through said stretch, said signals acting to divide said stretch into a plurality of track sections, track relays for each of said sections, a polarized signal relay for each of said signals, an energizing circuit for each of said polarized signal relays controlled by front contacts of the track relays for the track section next in advance of its associated signal and in accordance with traffic conditions in advance of that section for normally energizing said signal relay with positive potential, a directional stick relay associated with each of the intermediate signals for applying negative potential to the energizing circuit for the polar signal relay for the signal next in the rear while the track section in advance of that intermediate signal is occupied by a train which passes it in a direction governed by such intermediate signal, manually controlled means associated with each starting signal for holding that signal at stop but acting when operated to allow such sig-

nal to clear and at the same time to deenergize the circuits of the signal relays for all signals governing traffic in the opposite direction, an approach relay associated with each of said starting signals and included in series with the polarized signal relay for the first intermediate signal governing traffic toward the corresponding siding, a track indication relay associated with each of said starting signals, circuit means for each of said indication relays for energizing that relay when said signal relay for the associated starting signal is energized with positive potential, said circuit means also energizing said indication relay if such signal relay is deenergized providing the associated approach relay is energized, whereby each indication relay is deenergized whenever a train is approaching the corresponding siding within the adjacent track section or is travelling away from the corresponding siding within the first two track sections of said stretch, a single track indicator in a central office for indicating when illuminated the occupied condition of said stretch as a whole, and circuit means effective to illuminate said track indicator when either or both of said indication relays is deenergized.

10. In a single track railway system having a stretch of single track connecting two passing sidings, signals for governing traffic over said stretch of track in both directions including a starting signal at each end of the stretch and one or more intermediate signals dividing the stretch into track sections provided with track relays, a signal relay for each of said signals, an energizing circuit for each of said signal relays controlled by track relay contacts for the track section next in advance of its associated signal and in accordance with traffic conditions in advance of that section, manually controlled means associated with each starting signal for holding that signal at stop but acting when operated to allow such starting signal to clear dependent upon the energized condition of its associated signal relay and at the same time acting to deenergize the circuits for the signal relays for each of the signals governing the opposite direction of traffic, a single track indicator lamp in a central office for indicating when illuminated the occupied condition of said stretch, and circuit means con-

- 5 trolled by the signal relays for said two starting signals for energizing said indicator lamp only provided both of said signal relays are deenergized, whereby the manual clearing of one of said starting signals and the resulting deenergization of the signal relay for the other starting signal fails to effect the energization of said track indicator.
- 10 11. In a centralized traffic control system for a single track railway system having a stretch of single track connecting two passing sidings, a starting signal at each end of said stretch for governing the movement of traffic into said stretch from that end, at least one intermediate signal for governing traffic in each direction through the stretch and acting to divide said stretch into two track sections, track relays for said track sections, a signal relay for each of said signals, an energizing circuit for each of said signal relays including track relay contacts for the track section in advance of its associated signal and controlled in accordance with the signal control relay for the next signal in advance governing traffic in the same direction, a communication system connecting a central office with the ends of said passing sidings, manually controlled means effective through the medium of said communication system for holding said starting signals at stop but acting when operated to allow one or the other of said starting signals to clear dependent upon the energized condition of its associated signal relay and at the same time acting to deenergize the circuits for the signals relays for each of the signals governing the opposite direction of traffic, a single track indicator in the central office for indicating when illuminated the occupied condition of said stretch of track, indication means associated with each starting signal for transmitting an indication over said communication system to said central office when its signal relay is deenergized, and circuit means in the central office for energizing said track indicator only in response to the reception of an indication over said communication system that said signal relays for both said starting signals are deenergized.
